NECKTIE DISPLAY RACK

Reinhold J. Anderson, Red Oak, Iowa

Application August 24, 1954, Serial No. 31,980

Term of patent 14 years

(Cl. D80—9)

Fig. 1.

Fig. 2.

Fig. 3.

To all whom it may concern:

Be it known that I, Reinhold J. Anderson, a citizen of the United States, residing at Red Oak, in the county of Montgomery and State of Iowa, have invented a new, original, and ornamental Design for Necktie Display Rack, of which the following is a specification, reference being had to the accompanying drawing, forming a part hereof.

Figure 1 is a perspective view of a necktie display rack showing my new design.

Figure 2 is a side elevational view of the rack.

Figure 3 is a plan view of the rack.

I claim:

The ornamental design for a necktie display rack, as shown.
